DESIGN FOR A COMBINED SINK AND CABINET

Clarence Karstadt, Glen Ellyn, Ill., assignor to
American Central Manufacturing Corporation,
Connersville, Ind., a corporation of Indiana

Application December 9, 1943, Serial No. 111,961

Term of patent 14 years

To all whom it may concern:

Be it known that I, Clarence Karstadt, a citizen of the United States, residing at Glen Ellyn, in the county of Du Page and State of Illinois, have invented a new, original, and ornamental Design for a Combined Sink and Cabinet, of which the following is a specification, reference being had to the accompanying drawing, forming a part thereof.

In the drawing:

Figure 1 is a perspective view from one side and end of a combined sink and cabinet showing my new design; and Figure 2 is a plan view of one-half of the top, the other half being symmetrical.

I claim:

The ornamental design for a combined sink and cabinet, substantially as shown.

CLARENCE KARSTADT.
